Patented Aug. 17, 1920.

Inventor
Pincus Rice
By his Attorney
Paul M. Klein

UNITED STATES PATENT OFFICE.

PINCUS RICE, OF NEW YORK, N. Y.

CALENDAR.

1,350,114.

Specification of Letters Patent. Patented Aug. 17, 1920.

Application filed September 10, 1919. Serial No. 322,894.

To all whom it may concern:

Be it known that I, PINCUS RICE, citizen of the United States, and resident of New York city, in the county of New York and State of New York, have invented certain new and useful Improvements in Calendars, of which the following is a specification.

This invention relates to calendars and particularly to the so called perpetual calendar.

The objects of my invention are to provide a simple, inexpensive and handy mechanism which may be easily operated, and which, in view of its primitive construction, is not liable to get out of order.

Other objects are to provide a mechanism so constructed, as to be operable by a frictional or gear-engagement combined with a rotary motion, while eliminating any sort of spring actions, locking arrangements or similar devices which, in the course of use might fail to function.

Still other objects are to provide means whereby the calendar casing may be easily attached to or detached from a typewriter frame or any other object where a calendar is of importance.

The above and further objects will appear more fully in the following specification and from the accompanying drawings, forming a part thereof, in which—

Figure 1 is an elevation of my device, attached to a typewriter frame.

Fig. 2 is an end view of same.

Fig. 3 is a sectional view of my device, taken on line 3—3 of Fig. 1.

Fig. 4 is an enlarged longitudinal cross sectional view of one preferred form of my device.

Fig. 5 is a similar sectional view of another form of my device.

Fig. 6 is a sectional view taken on line 6—6 of Fig. 4.

Referring to the figures, a typewriter frame 1, is shown, to which my calendar is attached by means of spring clamps 2 and 3, secured to the slidable base plate 4. The base plate shown in Fig. 5 is provided with countersunk holes 5 for receiving a screw or rivet with which the plate may be fastened to any desired article. As illustrated, the base-plate possesses turned-up extensions 6 provided with longitudinal grooves registering with guides 7 of the calendar casing 8.

This casing is provided at its semi-cylindrical upper part with apertures 9, 10, 11

and 12, in its side-walls with side-bearings 13, and with a central groove 14 for receiving a dividing center wall 15 equipped with a through-going center bearing 16 which is 60 alined with the end-bearings 13. Upon the outer surface of each of the side-bearings are mounted hollow cylindrical dating members 17 and 18, and upon each end of the through-going center bearings are secured similar 65 dating members 19 and 20. All of the cylinders are rotatable and in a slight frictional engagement with the bearings and are provided upon their outer surface with either paper strips 21 or other means for indicating 70 months, numbers and days.

Passing through the outer bearings into the center bearing are shafts 22 and 23 equipped with engaging members 24 and 25, which are securely fastened to the shafts by 75 set-screws 26. By pressing one of these engaging members toward a dating member, through shifting the respective shaft in the proper direction, that dating member may be turned, when the knurled knob 27 of the 80 shaft is turned, until set into desired position.

In Fig. 4 are shown engaging members of a double cone-shaped form corresponding with funnel-shaped dating members, which 85 extend beyond, or overhang their shorter bearings. In Fig. 5 is shown an engaging member of a different shape, having a rim 28 equipped at its edges 29 either with friction bands or teeth, for engaging similar 90 engaging means provided upon its corresponding dating members. In the latter form the part of the dating members resting upon the bearings may be of the same length as the latter.

Both constructions adhere to the basic principle of operating a perpetual calendar by means of a pair of slidable shafts having engaging members firmly secured to them, said members operatively engaging the dating mechanism of the calendar, one unit at the time, by shifting the shaft, and with it the engaging member, toward the one dating member and then turning the same by turning the shaft, until the desired words 100 or numbers appear within the apertures of the casing. In both cases the dating members are in slight frictional engagement with their respective bearings so as to prevent the dating members from voluntarily turning, 105 permitting them however to be operated by their respective engaging members. The

shafts in both constructions, when in extreme inward position, are not interfering with each other's operation.

As already indicated, the operation of my device is extremely simple and becomes self-evident from the construction shown in the drawings. It is however understood that changes or improvements, similar to the two modified forms illustrated in Figs. 4 and 5, may be made without departing from the broad principle of my idea. The same applies to changes or improvements of the attaching means for securing my device to various articles. Also the shape or construction in general shall not be limited to the forms shown, and changes may be made to meet different conditions or requirements within the broad scope of my invention.

Having thus described my invention and the principal features of its operation, I claim:

1. In a perpetual calendar operated by frictional devices, a main casing having side bearings, a center wall having a through going center bearing alined with said side bearings, two hand operated shafts, each passing through one side bearing and into the center bearing, double-cone-shaped friction members rigidly attached to said shafts between the bearings, dating members rotatably mounted upon the outer surfaces of the bearings and overhanging the same, permitting their engagement by said friction members.

2. The combination with a perpetual calendar, of a housing having end bearings, a slideable center wall inserted into grooves provided in said housing, a through-going center bearing provided in said center wall and alined with said end bearings, hand operated shafts passing through said end bearings into the center bearing, without touching each other, engaging members rigidly secured upon each of the shafts between the side bearings and center bearing, dating members rotatably mounted upon the outer surfaces of the bearings and operable independently by said engaging members at will, and means for attaching the calendar to a typewriter frame.

3. The combination with a perpetual calendar, of a calendar casing having inwardly projecting end-bearings at each end, apertures provided at one side of the casing, a center bearing alined with the end-bearings, dating-members rotatably mounted upon the outer surface of the bearings and frictionally engaging the latter, means provided

upon the outer surface of said dating-members indicating month, numbers and days, 60 said indicating means being visible in part through said apertures in the casing, an engaging member between the month indicating dating-member and one number indicating dating-member, another engaging member between the other number indicating dating-member and the day indicating dating-member, hand-operated shafts slidably and rotatably lodged in said bearings, each shaft having one engaging member rigidly attached thereto, a base plate for the casing, attaching means connected therewith for facilitating the fastening of the calendar to a desired object, said shafts, when pressed inward or pulled outward of the 75 casing and simultaneously turned, causing the engagement of said engaging members with, and the turning of said dating members to a desired position.

4. In a calendar of the class described 80 comprising a casing, inwardly extending bearings secured to the end walls of the casing, rotatable drums having upon their periphery dating characters mounted upon the bearings, and means disposed between 85 and normally out of contact with said drums and adapted for movement into positive engagement with either of said drums for actuating the same.

5. In a calendar of the class described 90 comprising a casing, inwardly extending tubular bearings secured to the end walls of the casing, members having upon their periphery dating characters rotatably mounted on the tubular bearings, and means 95 normally out of contact with the ends of the members and adapted to be optionally shifted into positive engagement with either of said members for actuating the same.

6. In a calendar of the class described 100 comprising a casing having side bearings, dating members rotatably mounted upon the outer surfaces of the bearings, and an operating shaft journaled and slidably mounted within the bearings having rigidly 105 secured thereon a member disposed between the dating members normally out of contact therewith whereby each of said dating members may be optionally actuated by a longitudinal and rotative motion of the operating shaft.

Signed at New York, in the county of New York and State of New York August A. D. 1919.

PINCUS RICE.
